(57) **CLAIM**

The ornamental design for a portal communication device, as shown and described.

DESCRIPTION

FIG. 1 is a perspective view of the portable communication device showing the first embodiment;

FIG. 2 is a front view of the portable communication device showing the first embodiment;

FIG. 3 is a rear view of the portable communication device showing the first embodiment;

FIG. 4 is a left side view of the portable communication device showing the first embodiment;

FIG. 5 is a right side view of the portable communication device showing the first embodiment;

FIG. 6 is a top view of the portable communication device showing the first embodiment;

FIG. 7 is a bottom view of the portable communication device showing the first embodiment;

FIG. 8 is a perspective view of the portable communication device showing the second embodiment;

FIG. 9 is a front view of the portable communication device showing the second embodiment;

FIG. 10 is a rear view of the portable communication device showing the second embodiment;

FIG. 11 is a left side view of the portable communication device showing the second embodiment;

FIG. 12 is a right side view of the portable communication device showing the second embodiment;

FIG. 13 is a top view of the portable communication device showing the second embodiment;

FIG. 14 is a bottom view of the portable communication device showing the second embodiment;

FIG. 15 is a perspective view of the portable communication device showing the third embodiment;

(Continued)

FIG. 16 is a front view of the portable communication device showing the third embodiment;
 FIG. 17 is a rear view of the portable communication device showing the third embodiment;
 FIG. 18 is a left side view of the portable communication device showing the third embodiment;
 FIG. 19 is a right side view of the portable communication device showing the third embodiment;
 FIG. 20 is a top view of the portable communication device showing the third embodiment; and,
 FIG. 21 is a bottom view of the portable communication device showing the third embodiment.

The broken lines depict portions of the portable communication device in which the design is embodied that are not part of the claimed design.

1 Claim, 18 Drawing Sheets
